(57) **CLAIM**

The ornamental design for a cleaning mitt, as shown and described.

DESCRIPTION

FIG. 1 is a top, right, front perspective view of a cleaning mitt showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a top, right, front perspective view thereof in a use state with open corner openings.

The broken lines in the Figures indicate stitching and form no part of the claimed design.

1 Claim, 6 Drawing Sheets(56)
